(57) CLAIM

The ornamental design for a golf ball mark repair tool, as shown and described in the accompanying drawings.

DESCRIPTION

FIG. 1 is a perspective view of the golf ball mark repair tool according to the preferred embodiment thereof;

FIG. 2 is a top plan view thereof, the bottom plan view is a mirror image;

FIG. 3 is an end view thereof,

FIG. 4, is a side elevational view; and,

FIG. 5 is a perspective view of a second embodiment of the golf ball mark repair tool as disclosed in FIG. 1. The undisclosed sides are identical to those disclosed in the first embodiment.
